THEODOR WOLFF, OF LEVERKUSEN, NEAR COLOGNE, GERMANY, ASSIGNOR, BY MESNE ASSIGNMENTS, TO GENERAL CHEMICAL COMPANY, OF NEW YORK, N. Y., A CORPORATION OF NEW YORK.

APPARATUS FOR THE CHEMICAL TRANSFORMATION OF GASES BY MULTIPLE-CONTACT ACTION AT REGULATABLE TEMPERATURES.

1,099,530.

Specification of Letters Patent.

Patented June 9, 1914.

Application filed January 16, 1913. Serial No. 742,489.

To all whom it may concern:

Be it known that I, THEODOR WOLFF, citizen of the German Empire, residing at Leverkusen, near Cologne, Germany, have invented new and useful Improvements in Apparatus for the Chemical Transformation of Gases by Multiple-Contact Action at Regulatable Temperatures, of which the following is a specification.

10 This invention relates to a novel apparatus for the chemical transformation of gases by multiple contact action at regulatable temperatures; and it comprises an apparatus made up of a plurality of compartments containing the contact material and a plurality of preheating or heat interchanging compartments arranged alternately and placed in direct communication with each other, or placed alternately one directly above the other, and provided with supply and distribution pipes leading the gas supply to the contact chambers directly, or through the heat interchangers at will, for the purpose of regulating the gas temperatures of the several compartments by exchange of heat between the incoming and outgoing gases; all as more fully hereinafter set forth and as claimed.

In the transformation of gases by contact action two separate contact chambers have heretofore been used with a preheater placed in advance of each; but such an arrangement has the disadvantage of requiring a complicated interposition of pipes and a plurality of separate and detached chambers in which and through which the regulation of the temperatures must be effected. By the present novel apparatus these disadvantages are obviated; and a simpler regulation of temperatures obtained. The present apparatus has the further advantages of greater simplicity of construction; of greater economy in construction and arrangement; and smaller loss of heat by radiation and resulting increase of smoothness of operation and ease of control.

The construction of the present novel apparatus is such that the contact compart-

ments and heat interchanging compartments are superposed and arranged alternately and in direct communication with each other in series, and advantageously also inclosed by the same surrounding casing. Two or more sets of contact and heat interchanging compartments can be thus arranged. The arrangement when more than two are used, however, is essentially the same as when only two are used, and accordingly in the present description and illustration the invention will be described with respect to two only.

The accompanying drawing illustrates somewhat diagrammatically, the novel apparatus of the present invention.

In this illustration the counter-current preheater 1 is placed below, and in direct communication with, the superposed contact chamber or compartment 3; and the counter-current preheater 2 is placed between, and in direct communication with, the two contact chambers 3 and 4. The chambers or compartments 4, 2, 3 and 1 are thus superposed and arranged in series in direct communication with each other. The mixture of gases to be transformed enter at 5. In the usual operation the valve 15 is kept continually open and by varying the amount of opening of the valve 6 the gas mixture will pass to a greater or less extent through the apparatus 1 and around the tubes and be thus preheated to the desired extent by the hot gases issuing through the tubes from the contact chamber 3. If the valve 6 is closed all the gas will pass through the heater; whereas if this valve is opened, the amount of such gas can be decreased at will. The gas mixture coming from the preheater through the pipe 8 mixes with the gas entering directly through the valve 6 and which can be regulated by this valve and passes through the pipe 9 into the branch pipe 10 and through the second preheater 2 to the contact compartment 4 and partly also if desired through the valve 11 and the pipe 12 into the same contact compartment. The gases passing into the preheater 2 are

heated by the hot gases passing downwardly through the tubes from the contact compartment 4, and then pass around the upper contact compartment 4 where they mix with those at the lower temperature in the mixing chamber 14 and thence flow into the contact compartment 4 where the contact reaction takes place.

The contact reaction whereby SO_2 is oxidized to SO_3 is a reaction accompanied by a definite but material evolution of heat. It is essential that this reaction be easily regulatable within the temperatures which permit most advantageous operation. With the present apparatus the temperatures of the incoming gases can be easily regulated by means of the bypass valve 11 up to the temperature of the reaction gases escaping from the contact compartment which temperature is obtained when the valve 11 is closed and all of the gas mixture passes through the preheater and around the contact compartment. Usually, however, it is desired that the gas mixture enter the contact compartment at a lower temperature, in which case more or less cooler gas is admitted through the pipe 12 to give the desired definite temperature. The surrounding of the contact compartment with preheated entering gas enables the temperature of this compartment to be more easily regulated, and prevents cooling by radiation. The provision of a mixing antechamber 14 also promotes the intimacy of mixture of the gases before entering the contact compartment. From the contact compartment the gases escape at a higher temperature, and partly converted, through the tubes of the preheater 2 where they serve to preheat the entering gases and where they are themselves cooled, and from which they pass at a definite temperature into the second contact compartment 3, where the reaction is completed. From this compartment they escape through the preheater 1 where they become cooled again and serve to heat up the incoming gases as already described. The arrangement is such that the gaseous mixture, after entering either through the pipe 10 or the pipe 12 or both, is kept entirely within the inclosing casing and passes successively and directly from one superposed compartment to the next and is finally discharged through the outlet 16, without cooling by radiation, and without passing through any external pipe connections. The temperature of the gases can be increased to their maximum obtainable when all the incoming gases pass first through the first preheater and then through the second; or any temperature up to the maximum can be definitely maintained by varying the amount of gases going through the preheater 2 and pipe 12, supplemented by the preheat-

ing to a greater or less extent of the gases in the preheater 1. Also the reduction in temperature of the hot gases flowing directly from the contact compartment 4 to the compartment 3 through the preheater 2 can be controlled by varying the amount and temperature of the cooler or partly preheated gases passing through the second preheater 2. Thus the amount of such gases entering through 10 into the preheater 2 is regulable by the valve 11, and the temperature of such gases by the extent of the preheating in the first preheater 1, this first preheater being thus supplemental to that of the second 2. A similar operation and control is effected when more than two sets of apparatus are used. Also the size, height and cubical capacity of the different compartments can be varied, as will be obvious. The inclosure of the different compartments in a common casing and the direct communication of the different superposed compartments with each other from the beginning of the first stage to the end of the last enables a definite temperature control to be easily obtained and maintained; and makes the apparatus simple and compact in construction and does away with the necessity of elaborate external pipe communications and detached compartments.

This apparatus may be used among other things for the production of sulfuric anhydrid from burner gases in the well-known way by the aid of platinized asbestos as catalytic material.

I claim:—

1. An apparatus for the contact treatment of gases by successive stages comprising a plurality of alternately superposed contact and heat interchanging compartments communicating directly with each other, means for supplying a gaseous mixture to the first of said contact compartments and means for passing any desired amount of said gaseous mixture through said heat interchanging compartments before entrance to the first contact compartment.

2. An apparatus for the contact treatment of gases by two stages comprising two sets of alternately superposed contact and heat interchanging compartments communicating directly with each other, means for supplying a gaseous mixture to the first of said contact compartments and means for passing any desired amount of said gaseous mixture through said heat interchanging compartments before entrance to the first contact compartment.

3. In an apparatus for the contact treatment of gases by successive stages, two superposed contact compartments, an intermediate heat interchanging compartment communicating directly with said contact compartments, a casing surrounding the up-

per of said contact compartments and spaced therefrom, and a communicating passage leading from said intermediate compartment to the top of the upper contact compartment between the sides thereof and said casing.

In testimony whereof I have hereunto set

my hand in the presence of two subscribing witnesses.
